PILLOW DELIVERY SLIDE STOP BRACKET
FOR TYPESETTING MACHINES

Emil Szubzda, New Bedford, Mass.

Application September 10, 1947, Serial No. 773,173

4 Claims. (Cl. 267—1)

1

This invention relates to a pillow delivery slide stop bracket for typesetting machines.

It is an object of the present invention to provide an adjustable spring cushion slide stop bracket for use adjacent the end of a track for the line delivery slide of a typesetting machine.

Other objects of the present invention are to provide a spring cushion stop for the line delivery slide which will cause the slide to come to a slow stop and to eliminate the breakage of matrices which often results from the shock which the delivery slide receives when coming to an abrupt stop on the present machines. The stop also prevents loose lines of matrices; prevents metal from squirting between matrices, and makes a smoother operation of the delivery carriage mechanism.

A further object is to provide a stop wherein there is provided a soft spring to take up the initial shock and then a final cushioning arrangement which comes into play to absorb the final shock.

Still further objects of the invention are to provide a spring cushioning device for a line delivery slide of a typesetting machine which is of simple construction, easy to install upon the slide track, inexpensive to manufacture, easily adjustable and efficient in operation.

For other objects and for a better understanding of the invention, reference may be had to the following detailed description taken in connection with the accompanying drawing, in which

Fig. 1 is a perspective view of my spring cushioning device mounted upon the track for a line delivery slide of a typesetting machine.

Fig. 2 is a longitudinal cross-sectional view taken through the track and looking in plan upon my spring tensioning device.

Fig. 3 is a side elevational view of my spring cushioning device.

Fig. 4 is a transverse cross-sectional view taken generally on line 4—4 of Fig. 2.

Fig. 5 is a transverse cross-sectional view taken through the device and on line 5—5 of Fig. 2.

Referring now to the figures, 10 represents a track for a line delivery slide of a typesetting machine, the end of which is open and into which there is extended and connected my spring cushioning device 11. Operable in the track is a line delivery slide 12 which is adapted to carry matrices and which is adapted to abut my spring cushioning device 11.

The attachment of the spring cushioning device 11 with the track 10 is effected by a bolt 13 which enters a longitudinally extending lug or portion 14 of a main body part 15 of the spring

2

cushioning device. In order to keep the spring cushioning device from pivoting on the bolt 13, there is inserted a pin 16 which enters an opening in the track and an opening in the projection 14. The body part 15 is internally threaded as indicated at 17 and through this there is extended a screw 18 which can be adjusted therethrough. This screw 18 has a central hole 19 therein through which extends a rod 21 having a head 22 adapted to be abutted by the delivery slide 12. The opposite end of the rod 21 is threaded at 23 to receive lock nuts 24 for retaining a plate 25 to which are connected springs 26. The forward ends of the springs 26 are connected to a plate 27 retained on the screw 18 by a lock nut 28. Accordingly when the head 22 is struck by the delivery slide, the shock will be absorbed lightly by the tension springs 26.

On the rod are disposed concaved washers or spring elements 31 which will also assume a part of the shock as the rod 21 is pushed through the threaded member 18. These washers 31 are arranged in pairs with their curved inner faces opposing each other and the pairs are spaced by 25 spacing washers 32.

In order to give additional resistance to the outward movement of the rod 21 there is provided on the rod a plate 34 which is retained against displacement thereon by lock nuts 35 and this plate is extended between side pieces 36 which are held together by a bolt 37 and nuts 38. The ends of these side pieces 36 are fastened by screws 39 to the body 15. A spring 41 is extended between the ends of the side pieces 36 whereby to retain the pieces 36 in frictional engagement with the sides of the plate 34 and to limit the return movement of the rod 21 to take up the shock as the delivery slide has come to rest and permitted to be returned.

While various changes may be made in the detail construction, it shall be understood that such changes shall be within the spirit and scope of the present invention as defined by the appended claims.

45 I claim:

1. A cushioning device for a line delivery slide of a typesetting machine comprising a body member having means thereon for the attachment of the spring cushioning device to the track of the line delivery slide, a threaded opening extending through the body, a threaded member in said opening and adjustable axially therethrough, said threaded member having a central hole, a rod 50 slidable through the central hole of the threaded member, a plate extending from the rod, a sec-

ond plate adjustable on the threaded member, spring means connected between the plates on the rod and the threaded member to take the shock of the delivery slide upon the rod, and other spring means on the rod ahead of the body member, a head on the rod adapted to abut the other spring means for also absorbing shock received from the line delivery slide.

2. A cushioning device for a line delivery slide of a typesetting machine comprising a body member having means thereon for the attachment of the spring cushioning device to the track of the line delivery slide, a threaded opening extending through the body, a threaded member in said opening and adjustable axially therethrough, said threaded member having a central hole, a rod slidable through the central hole of the threaded member, a plate extending from the rod, a second plate adjustable on the threaded member, spring means connected between the plates on the rod and the threaded member to take the shock of the delivery slide upon the rod, and other spring means on the rod ahead of the body member, a head on the rod adapted to abut the other spring means for also absorbing shock received from the line delivery

5 slide, side pieces extending rearwardly from the opposite sides of the body, a plate connected to the rod and adapted to have its ends engage with the side pieces on the body member to frictionally prevent the sudden return of the rod upon the slide coming to rest or removed from the spring cushioning device, spring tension means extending between the side pieces to retain them upon the edges of the friction plate.

5 3. A spring cushioning device for a line delivery slide of a typesetting machine as defined in claim 1 and said spring means on the forward end of the rod comprising convex washers arranged in opposing relationship and in pairs and with spacing elements between the same.

15 4. A spring cushioning device as defined in claim 2 and said plates on the rod and upon the adjustable threaded member being adjustable thereon and lock nut means for each of the respective plates for securing the same in locked position respectively on the rod and the adjustable threaded member.
